NOZZLE FOR DUODENAL PUMP TUBES

Clovis de Paiva Aguiar, Juiz de Fora, Minas Geraes, Brazil

Application October 27, 1942, Serial No. 463,506
In Brazil November 24, 1941

2 Claims. (Cl. 128—278)

The present invention relates to improvements in the nozzles of apparatus for the pump treatment of sinuous organic channels and, more particularly, in nozzles for duodenal tubular pumps.

Various different models of nozzles or tips to be attached to the thin and comparatively long rubber tubes of duodenal pumps are known in the art. Such nozzles are generally provided with a number of holes or slots distributed arbitrarily over approximately the whole surface of the nozzle body, usually with some of the holes provided at or near the forward end of the nozzle. These known nozzles are advanced through the body channels which are to be intubated by means of the gravity of the nozzle aided by the peristaltic movements of the stomach and intestines in case of a duodenal tubular pump. With the known duodenal pump nozzles, the progress of the nozzle through the body cannot be accelerated by the discharge of liquid through the nozzle, and where such discharge takes place before the intubation has been completed, it actually retards the advance of the nozzle thereby prolonging the operation and causing fatigue and suffering to the patient.

It is one object of the present invention to eliminate this inconvenience as much as possible.

Another object of the invention is to provide a new nozzle for a duodenal tubular pump which facilitates and accelerates the forward progress of the nozzle and attached tube through the sinuous body channel leading into the duodenum.

Another object of the invention is to provide a nozzle for an intubating apparatus which permits the discharge of liquid from the nozzle before the latter has reached its final position within the body cavity to be intubated without impairing the progress of the nozzle and attached tube through the body.

Still another object of the invention is to facilitate the intubation of sinuous body cavities by means of a nozzle designed to permit acceleration of its forward progress through a body channel by the discharge of liquid from the nozzle during its forward movement through the organic channel.

A still further object of the invention is to provide a duodenal tubular pump with a nozzle ensuring greater rapidity of the operation and, consequently, less discomfort for the patient.

These and other objects are accomplished, according to the invention, by the arrangement and combination of parts set forth in the following detailed description, defined in the appended

claims and illustratively exemplified in the accompanying drawings in which:

Fig. 1 is an elevational-side view of a duodenal pump nozzle according to the invention,

Figs. 2 to 4 are longitudinal sections through three different embodiments, respectively, of nozzles according to the invention.

Fig. 5 shows a nozzle according to the invention attached to the tube of a duodenal pump of the usual type, and

Fig. 6 illustrates diagrammatically the progress of a nozzle and tube according to the invention through the stomach and into the duodenum of a patient.

15 As shown in Fig. 1, a nozzle according to the invention consists generally of an oval body 11 having a narrow neck 12 provided with peripheral grooves 13 which serve to secure the nozzle in the usual rubber tube 14, as shown in Fig. 5. The tube 14 is provided at predetermined points along its length with markings 15, 16, 17 to indicate to the operator the position of the nozzle during the progress thereof through the body.

20 In each of the nozzles illustrated in Figs. 2 to 4, a pumped fluid may enter the body of the nozzle through an axial inlet passage 18 extending through the neck 12 and terminating inside of the body 11 of the nozzle at a point near the tip thereof, and the fluid is discharged in a generally 25 rearward direction through orifices 19 provided in the rear portion of the body 11.

In the embodiment of the invention illustrated in Fig. 2, the forward end of the axial inlet passage communicates with the forward ends of a plurality of discharge channels 20 arranged parallel to the axis of the nozzle and to the axial passage 18 and opening at their rear ends into the orifices 19.

According to Fig. 3, the inner surface of the nozzle opposite the forward end of the axial passage 18 is provided with a rearwardly pointing deflector surface 21 which has its apex disposed in alignment with the axis of the nozzle and includes concave walls to guide the fluid emerging from the forward end of said inlet passage smoothly 40 towards said parallel discharge channels 20.

In the embodiment according to Fig. 4, the nozzle is provided with a rearwardly pointing deflector surface 21, as in Fig. 3, but, in this case, the discharge channels 22 which connect the forward end of the inlet passage 18 with the orifices 19 are not parallel to the axis of the nozzle but diverge rearwardly from said axis.

50 In use, a duodenal pump provided with a nozzle according to the invention, is introduced into

the stomach of the patient in the usual manner. As soon, however, as the nozzle 11 has reached the stomach liquid and air are injected into the nozzle 11 through the tube 12 under a certain pressure at frequent intervals, until the nozzle has reached the desired position in the duodenum. Due to the internal shape of the nozzle, the liquid, thus injected under pressure, is forced to spurt out in fine strong jets from the rear part of the nozzle, as indicated by the arrows in Figs. 2 to 4, thus producing a forward propelling action similar to that utilized in rocket propulsion, thus facilitating and accelerating the forward progress of the nozzle and attached tube from the stomach into and partly through the duodenum (see Fig. 6).

Since the value of the propelling force exerted by the fluid jets emerging from the nozzle 11 upon the latter and the attached flexible tube 14 increases in inverse ratio to the angle formed by the jets with the axis of the nozzle, particularly good propulsion effects are obtained with nozzles in which the discharge channels 20 are arranged parallel to the axis of the nozzle and outside of the outer periphery of the neck 12, as shown in Figs. 2 and 3.

Another way for obtaining a good forward propelling efficiency is to provide inside of the nozzle a deflector surface as shown in Figs. 3 and 4 which serves to guide the liquid emerging from the inlet passage smoothly into the discharge channels 20, 22, thus eliminating losses of energy due to swirling.

Nozzles according to the invention may be used not only for duodenal pump tubes but also for the intubation of other sinuous body channels with such modifications as may be necessary in each case.

The nozzles according to the invention may be propelled forwardly by means of the injection of liquid only into the nozzle. A greater efficiency, however, is obtained if a liquid and a gas, such as air, are injected in succession under a certain pressure. The moment of maximum propulsion is then that which coincides with the sudden release from pressure of the gas after the last portion of the liquid has passed out from the nozzle through the orifices 19.

A satisfactory result is obtained if water and air are injected into the flexible tube 14 by means of an ordinary syringe or similar injector.

Care must be taken in each case that the nature of the fluids, the pressures and the volumes employed are such as are perfectly tolerated by the organism.

I claim:

1. In an apparatus for the pump tube treatment of sinuous organic channels, the combination with a flexible tube, of a nozzle, comprising a bulb-shaped body having a rounded forward end and, at its rear end, a short neck of reduced diameter to which said flexible tube is attached, said nozzle being provided with an axial inlet passage leading through said neck into said body, and a plurality of discharge channels of relatively small diameter communicating inside said body with said inlet passage, all of said discharge channels emerging from said body in a generally rearward direction and being so arranged that jets of fluid emitted from said discharge channels emerge from said body in a direction substantially parallel to the axis of the latter and outside of the outer periphery of said constricted neck, whereby the introduction of a fluid under pressure through said tube into said nozzle and the emission of such fluids through said discharge channels tends to exert a forwardly propelling force on said nozzle and the attached flexible tube.

2. In an apparatus for the pump tube treatment of sinuous organic channels, the combination with a flexible tube, of a nozzle, comprising a bulb-shaped body having a rounded forward end and, at its rear end, a short neck of reduced diameter to which said flexible tube is attached, said nozzle being provided with an axial inlet passage leading through said neck into said body to a point near the forward end thereof, a plurality of discharge channels of relatively small diameter communicating inside said body with said inlet passage and all emerging from said body in a generally rearward direction, and a rearwardly pointing deflector surface carried on the inside of said body opposite the forward end of said inlet passage, said deflector surface having its apex disposed in alignment with the axis of said nozzle and including concave walls to guide the fluid emerging from the forward end of said inlet passage smoothly towards said discharge channels.

CLOVIS DE PAIVA AGUIAR.
